MANUALLY OPERATED PROPELLING MEANS
FOR BOATS AND THE LIKE

Harry M. Hall, Akron, Ohio, assignor of fifty percent to J. S. Applegate, Wellsville, W. Va., and twenty-seven and one-half percent to Orpha E. Lyda, Canton, Ohio

Application May 8, 1942, Serial No. 442,191

2 Claims. (Cl. 115—24)

The invention relates to manually operated propelling means or apparatus for boats and the like, and particularly lifeboats, and includes improvements of U. S. Letters Patent No. 2,149,850, issued March 7, 1939, to Arthur W. Lyda, for Life-boats.

In the hand operated mechanism by means of which the passengers or crew of the boat of said Lyda patent may drive the propeller shaft, the operators of the mechanism stand in the aisleway between the seats, alternately facing opposite sides of the boat and grasp hand grips on the operating levers of the drive mechanism, rocking the levers back and forth transversely of the boat in order to rotate the drive shaft through levers and spur gearing.

The necessity for the operators to stand and face the opposite sides of the boat is tiring and requires the operators to twist their necks and bodies in order to observe the course of the boat.

Moreover, the mechanism of said Lyda patent can turn the drive shaft in either direction, and the operators do not know which direction the drive shaft and thus the propeller will turn until after the shaft rotates, and also in the mechanism of said Lyda patent the gears are exposed.

The objects of the present invention include the provision of manually operated propelling means for boats and the like, and which may be operated by persons seated on usual transfer seats of a usual lifeboat with all the operators facing in one direction.

Further objects of the present invention include the provision of improved manually operated drive means particularly adapted for use in driving the propeller of a boat, and in which the drive shaft can only be driven in one direction, and including a balancing flywheel, and reversing means whereby the driven propeller shaft may be selectively rotated in either direction, and which includes housings enclosing the gears and other working parts.

The foregoing and other objects are attained by the manually operated propelling means, mechanism, apparatus, parts, combinations, and sub-combinations, which comprise the present invention, the nature of which is set forth in the following general statement, and preferred embodiments of which together with their mode of use are set forth by way of example in the following description, and which are particularly and distinctly pointed out and set forth in the appended claims forming part hereof.

The nature of the present invention may be stated in general terms as including preferably

in a boat, manually operated propelling apparatus particularly adapted for propelling the boat including a drive shaft, manually operated means for rotating the drive shaft, means limiting rotation of the drive shaft to one direction, a driven shaft, helical gear means operatively connecting the drive shaft and the driven shaft, a propeller shaft, a propeller on the propeller shaft, a flywheel on one of the shafts preferably the driven shaft, and reversing gear means operatively interposed between the driven shaft and the propeller shaft.

The helical gear means and the rotational direction limiting means are preferably enclosed by a housing frame including bearing means for the drive and driven shafts, and the drive shaft and driven shaft and their associated parts preferably constituting a step-up gear unit.

Likewise, the reversing gear means is preferably in the form of a reversing gear unit enclosed in a housing frame providing bearings for the shafts of the unit.

By way of example, a preferred embodiment of the improved manually operated propelling means or apparatus for boats and the like is illustrated in the accompanying drawings forming part hereof, in which

Figure 1 is a top plan view of a lifeboat equipped with propelling apparatus including the present improvements;

Fig. 2, a longitudinal vertical sectional view thereof, as on line 2—2, Fig. 1;

Fig. 3, a detached vertical sectional view, as on line 3—3, Fig. 4, of the preferred improved step-up gear unit of the apparatus, with portions broken away and shown in section; and

Fig. 4, a transverse sectional view thereof, as on line 4—4, Fig. 3.

Similar numerals refer to similar parts throughout the several views.

The lifeboat indicated generally by 10 in Figs. 1 and 2, as shown includes a one-piece steel bar formed as a keel 11, a stern 12, and a stern post 13 and upon which is secured in a usual manner a steel shell or hull 14 provided with upper gunwales 15 and 16.

Within the shell 14 are located and secured in a usual manner a plurality of thwarts 17 which extend across the boat and provide seats for the passengers and crew.

Side benches 18 and 19 extend across the tops of the thwarts at opposite ends thereof, and the benches merge at the ends of the boat in a bow deck 20 and a stern deck 21.

Steel braces 22 and 23 preferably extend be-

tween the gunwales and the ends of the thwarts.

In the bottom of the boat a plurality of longitudinally spaced Z bars 24 extend crosswise and support on their upper ends a plurality of floor boards 25.

The keel 11 includes a stern extension 26 extending below the stern post 13, and on the stern post 13 and the keel stern extension 26, a rudder 27 is operatively mounted and provided at its upper end with a tiller 28.

The improved manually operated propelling apparatus for the boat includes a step-up gear unit indicated generally by 29 mounted on a suitable base 30 on the bottom of the boat shell 14. In the center portion of the boat the thwarts are arranged in closely arranged pairs, and for purposes of convenience and compactness, the step-up gear unit 29 is preferably located below the after pair of thwarts 17.

The step-up gear unit 29 includes a housing and mounting frame 31 in which is journalled a transverse drive shaft 32 having ends extending beyond opposite sides of the housing 31, and the housing 31 also journals and operatively mounts a driven shaft 33 located above the drive shaft 32 and having an end 34 extending rearwardly towards the stern of the boat from the housing 31.

The driven shaft 33 of the step-up gear unit 29 is as shown and preferably located in the vertical plane of the keel 11, stern 12 and stern post 13, and the improved propelling apparatus furthermore includes likewise in the same vertical plane, a propeller shaft 35 alined with the driven shaft 33 and operatively mounted preferably as shown in a propeller bearing and mounting tube 36 extending through the stern post 13 and stern portions of the shell 14.

On the outside of the shell 14 and beyond the stern post 13, the propeller shaft bearing and mounting tube 36 is preferably supported by a strut 37 extending between the outer end of the tube 36 and the keel extension 26.

The propeller shaft 35 extends beyond the outer end of the tube 36 and terminates between the stern post 13 and the rudder 27, and on its stern extremity the propeller shaft 35 has secured thereon a propeller 38.

The forward end of the propeller shaft 35 is operatively connected with the rear end 34 of the driven shaft 33 of the step-up gear unit 29, and for the purposes of the present improvement there is preferably operatively interposed between the forward end of the propeller shaft 35, and the rear end 34 of the driven shaft 33, a reverse gear unit 39 controlled by a reversing lever 40 extending upwardly from the reverse gear unit 39 in the open space between the thwarts beneath which the step-up gear unit 29 is located and the next thwart toward the stern of the boat.

Also for the purposes of the present improvements, a flywheel 41 is preferably secured on one of the shafts preferably as shown on the rear end 34 of the driven shaft 33 of the step-up gear unit 29.

On the outer ends of the drive shaft 32 of the step-up gear unit 29 drive cranks 42 and 43 are secured, the crank angle between the longitudinal center lines of the cranks 42 and 43 being preferably less than 180° and as shown 90°.

Manually operated means for rotating the drive shaft 32 include the cranks 42 and 43 and lever and link means indicated generally by 44 operatively associated with the cranks 42 and 43.

As shown, the lever and link means 44 includes supported within the shell of the boat as 75

by brackets 45 and 46 depending from the thwarts 17, a longitudinally extending mounting and supporting beam 47 at one side of the gear units and shafts of the propelling apparatus 5 and above the crank 42, and parallel with the beam 47 at the other side of the gear units and shafts of the propelling apparatus, a similar mounting and supporting beam 48.

In each space between the central pairs of thwarts 17, and between the fore and aft pairs of thwarts 17 and the next single thwart as shown, each beam 47 and 48 has formed therein a longitudinally extending slot 49 on opposite sides of which are secured on its beam a pair of laterally spaced pivot mounting brackets 50.

Between each pair of spaced mounting brackets 50 an operating lever 51 extends through its slot 49 and above and below its supporting and mounting beam 48 or 47, and each operating lever 51 is pivotally mounted in its brackets 50 as by a pivot pin 52 whose pivot axis extends crosswise of the keel.

Below the beams 48 and 47 each lever 51 has operatively mounted therein a pivot pin 53, the axes of each set of pivot pins 52 and 53 being parallel and having the same spacing as the other sets, and the pivot pins 53 of the levers 51 at the side of the boat above the drive crank 42 are pivotally connected in equally spaced pivot apertures formed in a drive bar 54; and similarly the pivot pins 53 of the lever 51 at the other side of the boat above the drive crank 43 are pivotally connected in equally spaced apertures formed in a drive bar 55.

The two levers 51 immediately forward of the step-up gear unit 29 extend below the drive bars 54 and 55 respectively and are provided with lower pivot pins 56, and a pair of drive links 57 having equally spaced pivot apertures in their ends connect the drive pins 56, one with a crank pin 58 on the drive crank 42 and the other with a crank pin 59 on the drive crank 43, the crank pins 58 and 59 being equally spaced from the drive shaft 32.

The improved step-up gear unit 29 is detached and illustrated in detail in Figs. 3 and 4, and within the housing 31 the drive shaft 32 has keyed thereon a helical driving gear 60 which meshes with a helical driven pinion 61 preferably as shown formed integrally on the driven shaft 33.

For limiting rotation of the drive shaft 32 to one direction, within the housing 31 the drive shaft 32 has keyed thereon at one side of the helical gear 60 a ratchet 62, and a pawl 63 operatively mounted on and within the housing 31 for cooperation with the ratchet 62 in the usual manner.

In the operation of the improved propelling apparatus, all the passengers of the boat 10 may be seated facing in one direction on the thwarts 17, and those passengers opposite the upper ends of the levers 51 constitute the driving crew of the boat and by swinging or oscillating the levers 51 to and fro cause the unidirectional rotation of the drive shaft 32 and rotation of the propeller in the direction necessary to drive the boat forward or backward depending upon the setting of the reverse gear unit 39 by the control lever 40.

The flywheel 41 of the propelling apparatus provides momentum for the continuous rotation of the propeller 38 in the intervals when force is not being applied to the levers 51.

The rudder 27 is handled in the usual manner by one of the crew through the tiller 28.

The improved lifeboat 10 equipped with the improved manually operated propelling apparatus as above set forth thus enables all the driving crew to face either fore or aft, provides uni-directional rotation of the drive shaft, controlled reversing of the propeller, and protection of all the gears by the housings of the step-up gear unit and the reverse gear unit, and thus constitutes a practical and seaworthy manually operated propeller driven boat.

The embodiments of the present invention illustrated and described herein are by way of example and the scope of the present invention is not limited to the same or to the particular details thereof, but is commensurate with any and all novel subject matter contained herein which may at any time properly under the United States patent laws be set forth in the claims hereof or originating herein, and the elements of any such claims are intended to include their functional or structural equivalents.

I claim:

1. In a boat including a keel and a shell, thwarts extending transversely of the shell, brackets depending from the thwarts near each side of the boat, longitudinally extending supporting beams carried by said brackets, pivot mounting brackets located at spaced points upon said supporting beams, hand levers pivoted upon said pivot mounting brackets, a drive bar pivotally connected to the hand levers on each side of the boat, a drive shaft journaled transversely of the keel, crank arms upon opposite ends of the drive shaft, means connecting each crank arm to one of the drive bars, a spiral gear upon the drive shaft, a ratchet upon the drive shaft, a pawl co-

operating with the ratchet for limiting rotation of the drive shaft in one direction, a driven shaft extending in the same direction as the keel, a spiral gear upon the driven shaft meshing with the gear upon the drive shaft, a fly wheel upon the driven shaft, a propeller shaft extending in the same direction as the keel, a propeller on the propeller shaft, and reversing gear means interposed between the driven shaft and the propeller shaft.

2. In a boat including a keel and a shell, thwarts extending transversely of the shell, brackets depending from the thwarts near each side of the boat, longitudinally extending supporting beams carried by said brackets, pivot mounting brackets located at spaced points upon said supporting beams, hand levers pivoted upon said pivot mounting brackets, a drive bar pivotally connected to the hand levers on each side of the boat, a drive shaft journaled transversely of the keel, crank arms upon opposite ends of the drive shaft, one hand lever on each side extending beyond the corresponding drive bar, links pivotally connected to the extending portions of said hand levers and to said crank arms, a spiral gear upon the drive shaft, a ratchet upon the drive shaft, a pawl cooperating with the ratchet for limiting rotation of the drive shaft in one direction, a driven shaft extending in the same direction as the keel, a spiral gear upon the driven shaft meshing with the gear upon the drive shaft, a fly wheel upon the driven shaft, a propeller shaft extending in the same direction as the keel, a propeller on the propeller shaft, and reversing gear means interposed between the driven shaft and the propeller shaft.

HARRY M. HALL.
